MICROSCOPE

Jacob W. Patla, Rochester, N.Y., assignor to Bausch & Lomb Incorporated, Rochester, N.Y., a corporation of New York

Filed June 27, 1963, Ser. No. 75,547

Term of patent 14 years

(Cl. D57—1)

FIG. 2

FIG. 1

FIG. 3

FIG. 1 is a front perspective view from one side of a microscope embodying my new design;

FIG. 2 is a front perspective view from the other side thereof; and

FIG. 3 is a rear perspective view thereof.

The dominant features of my design reside in the portions shown in full lines.

I claim:

The ornamental design for a microscope, substantially as shown and described.
